UNITED STATES PATENT OFFICE.

DENNIS C. O'SHEA, OF CHICAGO, ILLINOIS.

GARMENT.

1,255,559.

Specification of Letters Patent.

Patented Feb. 5, 1918.

Application filed May 29, 1917. Serial No. 171,659.

To all whom it may concern:

Be it known that I, DENNIS C. O'SHEA, a citizen of the United States, residing at Chicago, in the county of Cook and State 5 of Illinois, have invented a new and useful Improvement in Garments, of which the following is a specification.

My invention relates to certain new and useful improvements in garments and is 10 fully described and explained in the specification and shown in the accompanying drawings, in which—

Figure 1 is a front elevation, and Fig. 2 a side elevation, of my improved garment as 15 the same is designed to be used.

Referring to the drawings, 3 is the body 20 of the garment, which is knitted as is common in sweater manufacture, with the ribbing running vertically and the direction of greatest elasticity, therefore, horizontal. 25 2 is the neck, which is made with what is termed in the trade a rack-stitch, about equally elastic in both directions and which, therefore, affords a snug fit around the neck. Attached to the upper end of the neck is 30 a hood. In this hood there is a central band 4 made with a rack-stitch, this band running from a point centrally located at the rear to the center of the forward upper edge of 35 the hood. The sides of the hood are made of two sections 5 and 6, in the position shown and with the ribbing running in the directions indicated. In both these the lines of greatest tension are naturally along the line 40 of the ribs. As a result, therefore, the ten-

sion in the part 5 tends to draw the center of the hood down snugly on the top of the head and the tension on the part 6 fits the hood snugly to the back of the head. There is thus secured not only an excellent fitting 40 garment but one having the extreme flexibility desirable in a garment intended for active outdoor pursuits.

I realize that considerable variation is possible in the details of the construction 45 herein shown, and I do not intend to limit myself thereto, except as pointed out in the following claim, in which it is my intention to claim all the novelty inherent in the device as broadly as is permitted by the state of 50 the art.

What I claim as new and desire to secure by Letters Patent is:

A sweater having in combination a knitted body portion, a neck portion knitted with a 55 rack-stitch to resist stretching in both directions, and a knitted hood having a central band running from the upper edge of the rear of the neck forward to the front upper edge of the hood and having its two sides 60 formed of sections ribbed in diagonally opposite directions from a central line, the ribbing in the rear portion of each side being substantially horizontal and the ribbing in the forward upper portion of each side 65 being substantially vertical, for the purpose set forth.

In testimony whereof I have hereunto set my hand this 5th day of May, 1917.

DENNIS C. O'SHEA.
